UNITED STATES PATENT OFFICE

HERBERT O. EWING, OF MIDDLEPORT, OHIO

INTERNAL COMBUSTION ENGINE

Application filed July 23, 1927. Serial No. 207,915.

This invention relates to an internal combustion engine of the two cycle type, one of the objects being to provide an engine of increased power and efficiency utilizing a vacuum cylinder which, by reason of the construction and operation of the engine, can be made much smaller than has heretofore been possible where vacuum has been utilized as a means for exhausting burned gases from the combustion chamber.

Another object is to provide an engine of the class described the cylinders and pistons of which can be lubricated in the usual way, that is to say, either by the splash or pump systems.

Another object is to utilize a vacuum cylinder and piston so assembled and operating that the piston can start with a practically zero clearance and will operate to expel all or practically all burned gases, the vacuum cylinder being so arranged that it will not be heated by the gases in the combustion chamber and can, therefore, be kept cool more readily than heretofore.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a section through the engine showing the relative positions of the parts at the beginning of the explosion stroke.

Figure 2 is a similar view showing the relative positions of the parts just prior to the completion of the explosion stroke.

Figure 3 is a similar view showing the relative positions of the parts at the beginning of the compression stroke.

Figure 4 shows the engine with the parts positioned during the first part of their movement from the positions shown in Figure 3.

Figure 5 is a section showing the positions

assumed by the pistons immediately following the positions illustrated in Figure 4.

Figure 6 is a section through the engine showing the parts positioned at the end of the compression stroke, the zero clearance in the vacuum cylinder being indicated.

Referring to the figures by characters of reference 1 and 2 designate the two cylinders of the engine communicating at one end with the crank case 3 and having their outer portions water cooled as indicated at 4. These cylinders can be cast in one block with their heads 5 and 6 removably mounted to give convenient access to the interiors of the cylinders. The cylinders are disposed at acute angles to each other so that the wall of the cylinder 2 will not be heated by the gases within the cylinder 1. Consequently the cylinder 2 can be maintained at a comparatively low temperature. Cylinder 1, which contains the combustion chamber 7, is provided with the usual spark plug 8 in the head 5 thereof while the head 6 of cylinder 2 has an outlet portion 9 communicating with an exhaust passage 10, the said port being normally closed by a valve 11 adapted to be lifted by pressure from within the cylinder 2. This valve is normally held to its seat by a spring 12, in the structure illustrated but it is to be understood that other types of valves may be used if desired.

At a point between its ends the cylinder 1 is provided with an intake port 13 and opening into the same cylinder at a point opposite the port 13 is a transfer passage 14 one end of which opens into the cylinder 2 as shown at 15 while the other end opens into the combustion chamber 7 as shown at 16. This end 16 constitutes the inlet to the port 14 and is enlarged in the direction of the head 5 as shown at 17. A power piston 18 is mounted for reciprocation within the cylinder 1 and is connected by a pitman 19 to the crank 20 in the case 3. Another piston 21 is mounted to reciprocate within the cylinder 2 and is connected by a pitman 22 to the pitman 19 as shown at 23. The ports 13 and 16 are so positioned relative to each other and to the head of the piston that, during a short interval while the engine is in operation the

piston will open communication between the passage 14 and the combustion chamber 7 while at the same time opening communication between the port 13 and the combustion chamber. These relative positions have been illustrated in Figure 3. The two pistons are so timed in operation due to the manner in which their pitmans are connected to the crank shaft, that at other times during the 10 operation of the engine, the piston 21 will close communication between the port 14 and the vacuum chamber 24 while at the same time the combustion chamber 7 is in communication with passage 14 and either in or 15 out of communication with the port 13 as shown in Figures 4 and 5 respectively. The proper lead of the piston in the vacuum cylinder 2 in its movement relative to the piston 18 in the combustion cylinder is insured because of the particular acute angle at which the two cylinders are arranged. The relative 20 positions of the parts at different stages during the operation of the engine are of importance as will be apparent in the following 25 description of the operation:

Assuming that the pistons 18 and 21 are in the positions shown in Figure 1, the piston 21 having moved downwardly from a zero clearance against the head 6 and an explosion having just occurred in the chamber 7, the two pistons will move downwardly under the power exerted by the expanded exploded gases in chamber 7. The particular pitman connection provided for the piston 21 will cause it to move downwardly past the port 15 so as to uncover it before the ports 13 and 16 have been uncovered. Consequently a vacuum will be produced within the chamber 24, the outside pressure serving to hold 40 the valve 11 tightly upon its seat. These positions of the parts have been illustrated in Figure 2. Immediately following this action the descending piston 18 uncovers first the port 16 and then the port 13. As a result the burned gases will rush into the passage 14 and thence to the vacuum chamber 24. This action, as well as the cooling and shrinkage of the burned gases following the explosion will cause the pressure within the 45 vacuum chamber as well as in the combustion chamber to be brought to several pounds below atmospheric pressure. During continued downwardly movement of the piston 18 following the partial uncovering of the port 16 and the escape of burned gases to the vacuum chamber, the intake port 13 is opened as shown in Figure 3. This will result in the admission of the explosive mixture and as atmospheric pressure is greater than the pressure within the cylinders the fresh supply of gas will flow automatically into the combustion chamber 7 where it will strike the deflector 25 on the piston 17 which deflector is located close to the port 13. Consequently the inrushing fuel, being subjected to very little

resistance from the gaseous contents of the engine, will flow easily toward the head 5 where it will be turned back and practically all of the remaining burned gases within the combustion chamber will flow into the port 16 and passage 14, leaving the combustion chamber almost entirely free of burned gases. As the new charge of cold gas enters the combustion chamber 7, it operates to further chill the cylinder 1.

Immediately following the admission of the charge of mixture to the combustion chamber, with the parts positioned as in Figure 3, the piston 21 moves upwardly slightly in advance of the piston 18 and closes the port 15 so that the unburned mixture now flowing into the combustion chamber and the port 13 cannot enter the vacuum cylinder.

As the gas within the chamber 7 was well below atmospheric pressure at the time the port 15 was closed by the piston 21, further gas can enter the combustion chamber 7 before the piston 18 fully closes the port 13. The amount of gas thus admitted will be sufficient to raise the pressure in the combustion chamber 7 to atmospheric pressure without resulting in any loss of gas through the port 16 and passage 14. The relative positions of the parts at this time have been illustrated in Figure 4. It might be stated that as the vacuum chamber was not restored to full atmospheric pressure during the foregoing operation, the resistance to the upward stroke of the piston 21 will be reduced and compression of the charge in the explosion chamber 7 will be facilitated. As the crank shaft moves from the position shown in Figure 4 both pistons will be moved toward the respective cylinder heads, thereby completely closing first the port 13 and then the port 16 as will be obvious by referring to Figure 5. Further movement will bring the piston 21 flat against the head 6 so as to produce zero clearance. The vacuum chamber is several pounds below atmospheric pressure until the piston has traveled far enough to overcome this sub-atmospheric pressure after which it creates a pressure great enough to open the spring pressed valve 11. It is on this stroke and due to this condition that a part of the energy required to produce the vacuum is restored to the crankshaft. Meanwhile the charge in the combustion chamber 7 is being compressed and at the end of the compression stroke this charge will be ignited so that the operation will be repeated as before described. The position of the piston 21 at the completion of its exhaust stroke has been illustrated in Figure 6.

Importance is attached to the fact that, as the port 15 closes before the gases in the chamber 24 reach atmospheric pressure, the sub-atmospheric pressure thus maintained will afford a substantial part of the energy

required to actuate the engine during the compression stroke.

In the present engine cooling occurs in the combustion chamber much the same as in other engines, except that it takes place much faster than in other engines because of the fact that the pressure drop is so much faster due to the sub-atmospheric pressure within the vacuum chamber to which the gas is so rapidly being transferred. Then too as this operation is progressing the pressure within the combustion chamber also goes from six to ten pounds below atmospheric. This has been disclosed by actual tests. This also

keeps down temperature. Many inventors have had in mind various means of handling this proposition all of which have differed from the present invention in that they provide means to use an auxiliary exhaust to the atmosphere, while with a high vacuum pressure I am able to handle and cool the full volume of burned gases. During low speeds I have no rush of burned gas back into the combustion chamber to relieve the sub-atmospheric pressure in the combustion chamber. This rush of air or gas back into the combustion chamber destroys the control of the pressure within the combustion chamber as well as causes the engine to miss fire due to the mixture with the burned gases. With my arrangement of engine, communication is cut off from the combustion chamber earlier than heretofore which permits the burned gases to cool better and drop farther below atmospheric pressure and so give back to the crank shaft more of the energy required to produce the vacuum, thus adding to the power output of the engine.

It is to be understood of course that the term "vacuum" used in the foregoing specification and in the appended claim is not intended to mean an absolute vacuum.

What is claimed is:

In a two-cycle internal combustion engine the combination with a power cylinder and a vacuum cylinder disposed at a relatively small angle to each other, of an intake port opening into the power cylinder, a valved exhaust port in the head of the vacuum cylinder, a relatively short passage connecting the cylinders at a point between their lower ends, a piston in the power cylinder for successively opening the cylinder to the passage and to the intake port during the explosion stroke and successively closing the intake port and the passage during the compression stroke, a piston in the vacuum cylinder, a crank shaft, a pitman connection between the crank shaft and the piston in the power cylinder, and a shorter pitman connection between the pitman of the power piston and the piston in the vacuum cylinder, said pitmans and crank shaft cooperating to actuate the vacuum piston to move from a zero clear-

ance and create a vacuum during the explosion stroke of the power piston and thereafter to open and close the cylinder to the passage, said passage being adapted to be closed by the vacuum piston prior to the compression of gases in the vacuum cylinder and before the closing of the intake port by the piston in the power cylinder.

In testimony that I claim the foregoing as my own, I have hereto affixed my signature.

HERBERT O. EWING.
